UNITED STATES PATENT OFFICE.

HARRY OGDEN McCLURG, OF BALTIMORE, MARYLAND.

NON-REFILLABLE BOTTLE.

No. 852,408.

Specification of Letters Patent.

Patented April 30, 1907.

Application filed August 8, 1905. Renewed October 2, 1906. Serial No. 337,133.

To all whom it may concern:

Be it known that I, HARRY OGDEN McCLURG, a citizen of the United States, and a resident of Baltimore, in the State of Maryland, have made certain new and useful Improvements in Non-Refillable Bottles, of which the following is a specification.

It is the object of my invention to provide a bottle with a new form of valve closure or stopper which shall permit the outflow of the liquid contents but effectually prevent the inflow of liquids, and which is so constructed and secured in the bottle neck that it cannot be removed therefrom, while the valves are so protected that it is impossible to reach them with an inserted tool or instrument.

The details of construction, arrangement and operation of parts are as hereinafter described, reference being had to the accompanying drawing, in which

Figure 1 is a longitudinal central section of a bottle neck and my improved stopper inserted therein. Fig. 2 is a perspective view of the main portion or hollow body of the stopper. Fig. 3 is a perspective view of that portion of the stopper which is adapted to be inserted in the hollow body portion shown in Fig. 2 and provided with a valve controlling the liquid-discharge opening.

Fig. 4 is a perspective view of another part of the stopper which includes a valve controlling the air vent and is adapted to be secured to the part shown in Fig. 3. Fig. 5 is a central longitudinal section of the stopper in a plane at right angles to the plane of section shown in Fig. 1. Figs. 6, 7, 8 and 9 are transverse or cross sections on the lines 6-6, 7-7, 8-8, and 9-9, respectively, of Fig. 1. Fig. 10 is a central vertical section of the bottle neck with my improved stopper inserted therein, a portion of the same being shown in side view and another portion broken away to show the interior construction. Fig. 11 is a perspective sectional view of a bottle neck with my improved stopper therein, the parts being inverted as required for the discharge of liquid.

In carrying out my invention—see Figs. 1 and 10—I provide a bottle neck A internally with an annular groove 1, and a shoulder 2, the same being duly spaced apart. My improved closure or stopper comprises—see Figs. 2 and 5—the following parts, to wit, a tubular body B, which is open at the bottom and provided at the top with an air

vent 3 and lateral openings 4 for discharge of liquid; a part C adapted to be inserted in the body B and cemented thereto and having a cylindrical base 5 and an elongated portion 6 provided with a liquid-discharge valve 6; a smaller part D having an air vent 7, and provided with a tenon 8 adapted to be inserted and secured in a socket 9 formed in the top of base 5 of part C; small tubes E and F, attached, respectively, to the head and base of the parts B, C, and serving as air vents or conductors; one or more balls G, which serve to open the air valve 7 of part D, when the bottle is inverted as required to discharge liquid; and annular, elastic, preferably cork, washers H, H', which are applied to the parts B, C, respectively. The washer H is held in the circumferential groove 1 formed in bottle neck A just below the liquid-discharge openings 4, and the other, H', abuts the shoulder 2 of the bottle neck. This shoulder 2, corresponds in function to the lower shoulder of groove 1, furnishing a stop for a washer. The washers are necessarily compressed when the stopper is inserted in the bottle neck A, and the upper one H expands into the groove 1 while the lower washer H' remains more compressed and assists in forming a liquid-tight closure.

The head of the tubular body B is constructed with a lateral flange 8 which prevents access of a tool to the upper washer H, while permitting escape of liquid as required.

The head of part B is provided below the lateral opening 4 with a vertical passage 9—see Fig. 1—which receives the tapered and flattened upper end 10 of part C, the flat side of the same being in contact with the flat side of said passage. The elongated vertical portion of part C is hollow and provided with an opening on the flat inner side, which opening is covered and normally closed by the thin, elastic, flat valve 6. This is secured at the lower end, the upper end being free to open to pressure of liquid. It may be cemented in place, and, for additional security, a thin, elastic washer 7^a, of cork or other material, may be inserted between the parts C and D, as shown in Fig. 1.

The flat top of part D is inclined and provided with an opening normally closed by the thin, elastic, flap valve 7, which is secured at the top by any suitable means, preferably by a U-shaped spring clamp.

The air vent tube E—see Figs. 5 and 10—

extends down to the part C, and the latter and the lower tube F constitute practically a continuation of the vent passage, through which air finds admission when the bottle is inverted and the liquid contents of the bottle are being discharged. In such case, the balls G roll against the valve 7, as shown by dotted lines in Fig. 11, thus opening it by pressure due to gravity, so that air has free admission.

When the bottle is held vertical or otherwise, so that the balls G are out of contact with the valve 7, as shown in Figs. 1 and 5, the valve remains closed.

15 The liquid passes out through the passage 10'—see Fig. 1—provided in the base 5 of part C, thence into the chamber behind the valve 6, which opens by reason of the pressure of the liquid, thus into the chamber of body B, and lastly through the passage 9 and opening 4 in the head of part B.

All the parts B, C, D, E, F, of the stopper, are constructed of glass, the tubes E, F, being cemented in place, and then the part C 25 inserted in and cemented to the inclosing part B, whereupon the stopper is ready for introduction in the bottle neck. The flap or plate valves 6 and 7 are preferably formed of mica, but other materials 30 may be used.

It is apparent that the lower shoulder of groove 1 in the bottle neck, may be dispensed with if the lower shoulder 2 be employed, since the stopper will be held in place as well 35 as if the groove 1 be retained; and, again, if the groove be employed, the lower shoulder 2 may be dispensed with, since it is only necessary to have two shoulders to prevent end-wise movement of the stopper when duly inserted.

What I claim is—

1. The combination, with a bottle-neck having interior shoulders spaced apart, of a stopper provided with washers spaced apart 45 corresponding to said shoulders, which they are adapted to engage, the stopper having also a discharge opening above the upper washer, and in its lower portion a passage that opens above the lower washer, and a 50 spring valve adapted to normally close such lower opening or inlet, substantially as described.

2. The combination, with a bottle neck provided interiorly with means for holding a 55 stopper in place, of a stopper comprising a tubular body having a washer and provided with a liquid passage extending and opening above and below the said washer, a hollow part arranged in said body and having a side 60 discharge passage and a spring-pressed valve applied to and adapted to normally close the said passage, substantially as shown and described.

3. The improved tubular stopper for non- 65 refillable bottles, comprising an upper por-

tion having a lateral opening and a lower portion having a lateral opening for discharge of liquid, a spring flap valve for normally closing the said lower opening, the said stopper being also further provided with an air vent 70 in the lower portion, substantially as described.

4. The improved stopper for non-refillable bottles, comprising a tubular body having an annular washer which is elastic and adapted 75 to spring outward for engaging the bottle neck, and also having a liquid discharge passage extending above and below the washer, said body being provided with a part having a side passage and a self-closing spring valve, 80 and a part having an air passage and a self-closing valve therefor, as described.

5. The combination, with a bottle neck, of a stopper adapted for insertion therein, and provided with means for forming a liquid-tight joint, the said stopper comprising a tubular body having a lateral discharge opening at the top and an attached part inserted in its chamber and comprising a lower portion having a passage for liquid and also having a lateral opening, a self-closing valve arranged to normally close such liquid passage, the said lower portion of the stopper having also an air-vent arranged substantially as described. 95

6. A stopper for non-refillable bottles, comprising a tubular body having a lateral opening at the top, a lower part provided with a passage for liquid, which passage has a lateral opening, a flap valve for normally closing such opening, and the said lower part having also an air-vent comprising a passage in the upper portion of the tubular body and a communicating passage in the lower portion of the stopper and a self-closing valve applied 100 for regulating admission of air to the lower passage, a movable weight arranged below said valve for applying pressure thereto, by gravity, when the bottle is inverted as described. 105

7. The improved stopper for non-refillable bottles, comprising a body portion having an opening at the top for discharge of liquid, and another opening for admission of air, a lower part having a lateral discharge opening, 115 and a valve normally closing the same, but adapted to open to pressure of liquid, said lower port being also provided with an air passage opening upward and having a spring valve for normally closing it, and a movable weight which applies pressure to such valve for opening it, when the bottle is inverted, substantially as described.

8. The improved bottle stopper for non-refillable bottles, comprising the tubular body, having openings at the top for passage of liquid and air, and a part inserted in the lower portion of the body and comprising a base which is secured to said body and provided with an elongated portion having a 120 125 130

passage and chamber opening laterally, a spring valve adapted to normally close the opening but yielding outwardly to pressure of liquid, and means for controlling the admission of air thus forming an air vent, substantially as described.

9. The improved stopper for non-refillable bottles, comprising a tubular body which is open at the bottom and provided at the top with air and liquid passages, a base portion provided with a liquid passage opening laterally and a spring valve for normally closing the same, also with an air passage and a valve for normally closing it, substantially as described.

10. In a stopper for non-refillable bottles, the combination, with a tubular body part having openings at the top for passage of air and liquid, of an inserted part which is in-

closed and protected by the body part, and comprises a base and an elongated portion having liquid and air passages and elastic valves for normally closing them, substantially as described.

11. The improved stopper for non-refillable bottles, comprising a tubular body portion having air and liquid passages in the top portion, a part, provided with air and liquid passages and elastic valves for closing them, which is adapted to be inserted and secured in the body portion, and tubes attached respectively to the body portion and the inserted portion and serving for conduction of air, substantially as described.
